CLAIM

The ornamental design for a formable vase, as shown and described.

DESCRIPTION

FIG. 1 is a perspective view of a formable vase showing our new design.

FIG. 2 is a perspective view thereof, shown in an alternate position of use;

FIG. 3 is a front elevation view thereof, the rear elevation view being a mirror image thereof; and,

FIG. 4 is a left side elevation view thereof, the right side elevation view being a mirror image thereof.
